PRESS SEALING HEAD FOR WRAPPING AND
SEALING EDIBLES

Payton A. Terry, Bristol, Va.

Application February 8, 1950, Serial No. 142,972

10 Claims. (Cl. 53—102)

1

This invention relates to a head for wrapping and sealing a plurality of articles and more especially confections such as pies, in a manner to quickly wrap and seal the edges of the wrapping about the articles. The articles are presented one after the other with a single sheet of sealable wrapping material such as cellophane, or two sheets of wrapping material may be provided for each article. These articles such as pies are comparatively flat.

An object of the invention is to provide a machine which will quickly seal an edible article, so as to hermetically seal the contents thereof from the atmosphere.

Another object of the invention is to provide a sealing and cutting head which in a single operation crimps the edges of the sealing paper such as cellophane around the outer circumference or edge of the confection, and as part of the operation, trims the material around said edges.

Yet another object of the invention is to provide a sealing and cutting head whereby in a single operation the layers of the paper above and below the article are caused to be crimped and sealed and simultaneously trimmed about the circumference of the article.

A further object of the invention is to provide a fringe of crimped paper which extends in substantially the same plane as the plane of the top surface of the confection after the trimming operation has taken place.

Additional objects will be found throughout the specification.

In the drawings.

Figure 1 is a perspective view of the head in position for receiving an article to be wrapped.

Figure 2 is a vertical section through the center of the head with parts shown in perspective.

Figure 3 is a top plan view of the lower section of the head and showing a broken away portion of the confection resting on said head.

Figure 4 is a horizontal section taken along the line 4—4 of Figure 2.

Figure 5 is a plan view looking upwardly on the line 5—5 of Figure 2.

Figure 6 is a side elevation of a wrapped confection and,

Figure 7 is a vertical sectional view partly broken away of the confection shown in Figure 6.

In the drawings A is the upper section of the head and B is the lower section of said head. The sleeve 1 is adjustably supported on the stationary support rod 2 by screw bolts 3.

2

Extending from the sleeve is an arm 4 for supporting the upper section A. This section has an upper portion 5, and attached below the shoulder 6 is a cutting ring 7 which is removably attached to upper portion 5 by one or more screws 8 as seen in Figure 2.

The lower end of the cutting ring is provided with a beveled portion 9 which ends in a cutting edge 10.

10 Mounted within the space 11 formed by the ring 7 is a former 12. This former is moved downwardly by one or more coiled springs as indicated by the numeral 13. The lower ends of these springs are seated in recesses 14 in the former and their upper ends bear against the flat under side 15 of the upper portion 5. The springs continuously force the former in a downward direction. Downward movement, however, is arrested by rod 16. The stop rod 16, which is 15 provided with a head 17 that seats in a lower recess 18 of former 12. There is an additional lower recess 19 for heating plate 20 as shown in Figures 2 and 5.

20 Relative movement by the stop rod 16 and upper portion 5 is prevented by the stop screws 21. However, on occasion these screws may be loosened so as to provide for relative adjustment of rod 16, head 17 and the tension of the springs 13.

25 It will be noted that the former "floats" within the space 11.

30 Preferably spaced circumferentially about the stop rod 16 are a plurality of heating rods 22. The lower ends of these rods extend substantially to heating plate 20, and they are fixed to the former, so that they too float with the former in space 11. In doing so, they slide in recesses 23 in upper portion 5. The heating rods are provided with heads 24, and said heating rods are 35 also provided with suitable electric conductors 25 that may be connected to any suitable source of electrical potential, not shown.

The floating former 12 is provided with a circumferential series of teeth 26 which extend 40 from the lower peripheral edge upwardly which terminate at the shoulder 27. These teeth have horizontal extensions 28. These horizontal extensions terminate at the additional lower recess 19.

45 It will be noted that the lower inner periphery of the cutting ring 7 is provided with a circumferential series of vertical teeth 29 which extend all the way or just about all the way to the cutting edge 10, so that this cutting edge itself 50 is serrated.

The entire upper section A is stationary except the floating former 12 and the springs 13 and heating rod 22 that move with it, during the upward movement of the lower section B now to be described.

This lower section is also provided with teeth 30 which extend peripherally around the lower section. These teeth have horizontal extensions 31 which mesh with horizontal extensions 28 during the forming operation. Since the horizontal portions 28 of teeth 26 mesh with horizontal portions 31 of teeth 30, the cutter's internal teeth 29 may engage teeth 30 when the former has been caused to move upwardly by the upward movement of the lower section B.

A stop rod 32 is provided for the lower section having a head 33 which is adapted to be moved into the recess 34 of said lower section, as the head moves up, the rod being stationary.

The head is provided with internal slanting sides 35 in the present instance, which support a pie to be sealingly wrapped when the upper and lower sections A and B come in contact with each other, and the cutting edge 10 moves past or reaches the junction line 50 of the series of vertical teeth 29 and teeth extensions 30 of the lower section. Former teeth 26 mesh with cutting ring teeth 29 at all positions of the parts.

The lower section may be heated by any suitable means such as the circular heater 36 that is located in the recess 37. This heater is provided with a conductor 38 that may be connected to the same potential as the conductors 25.

In operation, a series of unwrapped pies may be fed, one after the other, to the head; but first, each pie has been fed into a loop of cellophane so that the cellophane extends at the top and bottom thereof, or conversely, separate sheets of cellophane may be fed with the pie to the head. This operation may be done either manually or may be performed by suitable mechanism, not shown. There are various machines for feeding articles and papers together to a forming head and the present invention is not concerned with such machines, as see Hausheer Patent No. 2,232,783, February 25, 1941.

Once the pie has been positioned with the paper both above and below it on the head 33, the lower section B of the head is moved upwardly. At this time the head 33 of rod 32 is about level with the lower edge of the slanting sides 35. The lower section moves upwardly until teeth 28 engage teeth 31 in meshed relationship and cause former 12 to move upwardly within space 11. This action continues until teeth 29 abut teeth 30 whereupon the cutting edge reaches or passes the junction line 50 of teeth 30 and 31 to perform the severing function.

At this time, assuming that the heating rods have heated the former 12 and the circular heater has heated the lower section, particularly slanting sides 35, a sealing and crimping action takes place to seal the two layers of paper and crimp them. Substantially simultaneously the cutting edge 10 severs the crimped and joined circumferential paper extensions. These paper extensions have been indicated by the letter E in Figures 6 and 7.

Following this operation the lower section descends, by a suitable mechanism, not shown. The rod 32 is caused to move upwardly in the lower head to eject or move the pie out of the depression formed by the slanting sides 35.

It will be noted that the vertical teeth on the cutting ring, and the vertical and horizontal

teeth on the former and lower section B cause proper crimping of the extension E of the cover and that these teeth also perform the very important dual functions of completely sealing the edges of the sheets of paper which form this extension so as to seal the article, and properly guide the former and lower section with regard to each other as well as the cutting ring on the lower section B.

10. It should be understood that other guide means may be used than the vertical and horizontal teeth shown, and that the particular width of these teeth is of no consequence except that they should mesh with each other so as to prevent 15 relative movement between the parts when the upper and lower sections of the head are in engagement. It should also be understood that it is not desired to limit this invention to the exact construction shown as the shape of it may 20 be changed according to the shape and size of the confection to be wrapped.

The description and drawings are therefore to be construed in an illustrative rather than a limiting sense, as I desire to be limited only to 25 the extent set forth by a reasonable interpretation of the appended claims.

I claim:

1. A head for applying a covering to an article and for sealing the edges of the covering comprising a pair of relatively movable sections comprising an upper section and a lower section, a cutting and trimming ring mounted on one of said sections, a former mounted within said ring and means for crimping and sealing said covering around said article, said means including vertically extending guide members on the interior of said cutting and trimming ring, and cooperating guide means on said former engaging the first named guide means in meshed relationship.

40. 2. A head for applying a covering to an article and for sealing the edges of the covering comprising a pair of relatively movable sections comprising an upper section and a lower section, a cutting and trimming ring mounted on one of said sections, a former mounted within said ring and means for crimping and sealing said covering around said article, said means including vertically extending guide members on the interior of said cutting and trimming ring, and cooperating guide means on said former engaging the first named guide means in meshed relationship, and spring means for floatingly supporting said former within said ring.

55. 3. A head for applying a covering to an article and for sealing the edges of the covering comprising a pair of relatively movable sections comprising an upper section and a lower section, a cutting and trimming ring mounted on one of said sections, a former mounted within said ring and means for crimping and sealing said covering around said article, said means including vertically extending guide members on the interior of said cutting and trimming ring, and cooperating guide means on said former engaging the first named guide means in meshed relationship and vertically extending guide members on the other of said sections adapted to be engaged by said ring when said sections are in substantial engagement with each other.

70. 4. A head for applying a covering to an article and for sealing the edges of the covering comprising a pair of relatively movable sections comprising an upper section and a lower section, a cutting and trimming ring mounted on one of said sections, a former mounted within said ring

and means for crimping and sealing said covering around said article, said means including vertically extending guide members on the interior of said cutting and trimming ring, and cooperating guide means on said former engaging the first named guide means in meshed relationship and vertically extending guide members on the other of said sections adapted to be engaged by said ring when said sections are in substantial engagement with each other and mating crimping members on said former and the other of said sections.

5. A head for applying a covering to an article and for sealing the edges of the covering comprising a pair of relatively movable sections comprising an upper section and a lower section, a cutting and trimming ring mounted on one of said sections, a former mounted within said ring and means for crimping and sealing said covering around said article, a rod mounted in 20 said one section, a plurality of heating rods connected to said former, means mounting said former for relative movement in said one section and passageways in said one section for said rods permitting relative movement of said rods therein as said former moves in said section, said first named means including a plurality of vertical cooperating guide members on said ring, former and the other of said sections.

6. A head for applying a covering to an article, said head having an upper section and a lower section, a cutter mounted on one of said sections and a former mounted on said one section, said sections being adapted to be pressed together, means for biasing said former for movement toward said other section, and means for maintaining said former, cutter and sections in proper alignment with each other during said biasing and when pressed together, said last named means including guide members on the 40 interior of said cutter and cooperating guide members on said former engaging in meshed relationship said cutter guide means throughout said biasing and pressing movement.

7. A head for applying a covering to an article, said head having an upper section and a lower section, a cutter mounted on one of said sections and a former mounted on said one section, said sections being adapted to be pressed together, means for biasing said former for movement toward said other section, and means for maintaining said former, cutter and sections in proper alignment with each other during said biasing and when pressed together, said last named means including vertically extending guide members on the interior of said cutter and cooperating vertically extending guide members on said former engaging in meshed relationship said cutter guide means throughout said biasing and pressing movement, and means for crimping and sealing said covering, said means including parts on said former and other section adapted to mesh when said former and other section are in engagement with each other.

8. A head for applying a covering to an article, said head moving an upper section and a lower section, a cutter mounted on one of said sections and a former mounted on said one section, said sections being adapted to be pressed together, means for biasing said former for movement toward said other section, and means for

5 maintaining said former, cutter and sections in proper alignment with each other during said biasing and when pressed together, said last named means including vertically extending guide members on the interior of said cutter and cooperating vertically extending guide members on said former engaging in meshed relationship said cutter guide means throughout said biasing and pressing movement, and means for crimping and sealing said covering, said means including parts on each former and other section adapted to mesh when said former and other section are in engagement with each other, said parts on said former being extensions of said guide means on said former.

10 9. A head for applying a covering to an article, said head having an upper section and a lower section, a cutter mounted on one of said sections and a former mounted on said one section, said sections being adapted to be pressed together, means for biasing said former for movement toward said other section, and means for maintaining said former, cutter and sections in proper alignment with each other during said biasing and when pressed together, said last named means including vertically extending guide members on the interior of said cutter and cooperating vertically extending guide members on said former engaging in meshed relationship said cutter guide means throughout said biasing and pressing movement, and means for crimping and sealing said covering, said means including parts on each former and other section adapted to mesh when said former and other section are in engagement with each other, said parts on said former being extensions of said guide means on said former and means in both of said sections for heating said parts.

15 10. A head for applying a covering to an article and for sealing the edges of the covering comprising a pair of relatively movable sections comprising an upper section and a lower section, a cutting and trimming ring mounted on one of said sections, a former mounted within said ring and means for crimping and sealing said covering around said article, said means including vertically extending guide members on the interior of said cutting and trimming ring, and cooperating guide means on said former engaging the first named guide means in meshed relationship and vertically extending guide members on the other of said sections adapted to be engaged by said ring when said sections are in substantial engagement with each other and mating crimping members on said former and the other of said sections, said crimping members on said former being extensions of said cooperating guide means.
